United States Patent Office

Des. 191,982
Patented Dec. 26, 1961

191,982

DYNAMOELECTRIC MACHINE OR SIMILAR ARTICLE

Arlin C. Eisenhart, Fullerton, Calif., assignor to U.S.
Electrical Motors, Inc., Los Angeles, Calif., a corpora-
tion of California

Filed Jan. 24, 1961, Ser. No. 63,682

Term of patent 14 years

(Cl. D26—5)

Fig. 1.

FIG. 2.

FIG. 3.

FIG. 4.

FIGURE 1 is a perspective view of a dynamoelectric machine or similar article, showing my new design;

FIG. 2 is a side elevational view, to a reduced scale, the opposite side being substantially a mirror image thereof;

FIG. 3 is a top plan view, to a reduced scale; and

FIG. 4 is an elevational view taken from the left-hand end of FIG. 1, to a reduced scale.

I claim:

The ornamental design for a dynamoelectric machine or similar article, substantially as shown and described.
